CLAIM

The ornamental design for a user-configurable floor mat, as shown and described.

DESCRIPTION

FIG. 1 is a top elevational view of a generic grid of tiles, each of which is connected to at least two other tiles via said removably attachable connectors.

FIG. 2 is a top elevational view of a single tile, and a single removably attachable segment;

FIG. 3 is a top elevational view of four types of removably attachable connectors;

FIG. 4 is a top elevational view of a single tile with a single segment mounted internal to said tile, and four “null” connectors; and,

FIG. 5 is a top elevational view two tiles situated side-by-side, and connected via said removably attachable connectors.
